UNITED STATES PATENT OFFICE.

HEINRICH P. HEITMANN, OF ABLEMAN, WISCONSIN.

HEATING-DRUM.

SPECIFICATION forming part of Letters Patent No. 364,112, dated May 31, 1887.

Application filed February 3, 1887. Serial No. 226,407. (No model.)

To all whom it may concern:

Be it known that I, HEINRICH P. HEITMANN, a citizen of the United States of America, residing at Ableman, in the county of Sauk and 5 State of Wisconsin, have invented certain new and useful Improvements in Heating-Drums; and I do hereby declare the following to be a full, clear, and exact description of the invention, such as will enable others skilled in the 10 art to which it appertains to make and use the same, reference being had to the accompanying drawings, and to letters of reference marked thereon, which form a part of this specification.

15 This invention relates to heating-drums for stoves, and is designed as an improvement on the stove illustrated in United States Letters Patent No. 333,856, issued to me January 5, 1886.

20 The improvements will be described in detail in the following specification, and the novel features and combinations pointed out in the claims.

In the accompanying drawings, Figure 1 is 25 a diagrammatic view illustrating the relation between a heating-stove and drum, shown in section, and a stove remote from said drum. Fig. 2 is a horizontal section taken on line α α at the left hand of Fig. 1. Fig. 3 is a similar section taken on line y y , Fig. 1, just above the sliding dampers.

The heater B in apartment A may be a stove 35 of any preferred form—as, for instance, the cook-stove shown—and is to be fitted with a pipe, b , communicating with the chimney. Within another apartment, A', is a heating-stove, C, from which the top plate or cap is removed and replaced by a drum consisting of an outer shell, D, open at the bottom and 40 closed at the top, and an inner horizontal chamber, D', formed by walls d' , extending from side to side of the outer shell and terminating in openings therein. These openings in the outer shell are closed by doors d , to permit of closing the chamber D' at both ends, and affording access thereto when desired.

Near the top of the drum is a stove-pipe 45 collar, E, from which a pipe, e , leads to the chimney, and at a point just below the bottom wall of chamber D' is connected another pipe, F, leading from pipe b of heater B. The

passage leading to collar E is fitted with a damper, E', a damper, f , being also arranged in pipe F. At a point just below pipe F, and parallel with the bottom wall of chamber D', 55 is secured a support-plate, G, narrow guides g g being arranged a little above this support G at each end. Between the support G and guides g are arranged two horizontal slide-dampers, H H', so proportioned that both may 6 lie upon support G, to leave the passages g' and g'' at each side of the support open, or be adjusted to close one or both of said passages g' g'' , each damper being provided with an operating-rod, h h ', extending out beneath pipe 65 F, by which the proper adjustments of said dampers H H' may be made.

Pipe b is provided at a point above its junction with the branch pipe F with a damper, b' , by means of which said pipe b may be closed. 70

In practice it is designed that a fire will be constantly maintained in heater B, which represents the kitchen-range in a dwelling, so that when it is desired to but slightly modify the temperature in apartment A' the damper b' 75 may be closed, damper f opened, slide-dampers H H' adjusted to close the passages g' g'' , leading from the heater C to the drum, and damper E' opened, thereby causing the heated products of combustion to circulate through 80 the drum and pass to the chimney through pipe e . In colder weather, however, when the heat derived from range B is insufficient to heat apartment A', the damper f will be closed, damper b' opened, slide-dampers H H' 85 adjusted to open the passages g' g'' , and a fire be maintained in heater C. Should the fire in heater C render the apartment too warm, the damper E' may be closed and the damper f opened, thus conducting the heated products 90 of combustion from the fire in heater C through pipe F, and to the chimney through pipe b .

The chamber D' may be used as an oven for heating various articles; or the doors d may be thrown open to permit the heat in said 95 chamber to escape into apartment A'.

The drum is preferably constructed of sheet metal, and may be made to fit any usual form of stove, whether a wood or coal burner. Indeed, in many instances the heat received from 100 range B and radiated from the drum will be found sufficient to heat an apartment, as A',

at all times, and the heater C may be dispensed with. In such cases the various dampers will be arranged as first herein described.

To provide for the removal of soot and fine ashes that may lodge in the drum after passing damper E', I arrange within the drum a soot-box, I, leading downward from the space behind said damper, a door, i, being arranged at the lower end of said soot box, to afford access thereto.

I claim—

1. A heating-drum consisting, substantially as described, of an outer shell provided at one end with an exit and a damper for closing said exit and at the other end with passages, slide-dampers traveling in guides to open and close said passages, and an opening above said slide-dampers to afford communication with a stove or range.
2. A heating-drum consisting, substantially as described, of an outer shell provided at the bottom with a horizontal support, with slide-dampers and an opening above said support, and having an exit and damper at the top, a heating-chamber extending from side to side of the shell, and doors secured to the shell for closing both ends of the heating-chamber.
3. In combination with a stove or range having a main pipe and a branch leading therefrom, both fitted with dampers, and a heater

in another apartment, a drum consisting of an outer shell provided at top with a dampered exit leading to a chimney and at the bottom with passages leading from the heater, slide-dampers to open and close said passages, and an opening above said dampers to afford communication with the branch pipe from the range, substantially as described.

4. In combination with a stove or range having a main pipe and a branch leading therefrom, both provided with dampers, and an independent heater, a drum consisting of an outer shell provided at the bottom with passages leading from the heater and at the top with a dampered exit leading to the chimney, and at a point above the passages with an opening communicating with the branch from the range, slide-dampers traveling in guides to open or close the passages, a heating-chamber, the open ends of which terminate in openings at opposite sides of the shell, and doors fitted to said shell to close both ends of the heating-chamber, substantially as described.

In testimony whereof I affix my signature in presence of two witnesses.

HEINRICH P. HEITMANN.
